UNITED STATES PATENT OFFICE.

KOLOMAN REZSNY, OF BUDAPEST, HUNGARY.

FURNACE GRATE.

Application filed July 9, 1925. Serial No. 42,558.

To all whom it may concern:

Be it known that I, KOLOMAN REZSNY, a citizen of Hungary, and residing at Budapest, II, Hungary, have invented certain new 5 and useful Improvements in and Relating to Furnace Grates, of which the following is a specification.

This invention relates to furnace grates for fire boxes or flues of locomotive boilers of 10 the kind in which stationary side portions are used in combination with a tiltable portion, the centre of gravity of which latter portion is eccentric with respect to its axis of rotation, and in which no mechanical gear 15 is required for tipping the said movable part of the grate into the open position for the removal of the clinker and then again into its closed position the usual fire hook being sufficient for this purpose.

20 Furnace grates of the kind above referred to as hitherto constructed (see for instance Rezsny's Patent 1503767) have various drawbacks. Thus, the fire-bars are liable to break when striking against the stationary support 25 or abutment during a violent closure; when use is made of coal containing tar the movable and stationary parts may cake together at the supporting points and thereby render the upward tilting of the tiltable portion of 30 the grate more difficult and even prevent it altogether; the opened portions of the grate rest against the stationary parts thereof at an acute angle whereby a dead space is produced; the lifting of the arm of the tiltable 35 portion is rendered difficult by the weight of the clinker when the quantity of the residues is very large; the tilted arm projects into the fire box and interferes with the manipulation of the fire, etc.

40 The object of the present invention is to provide a construction in which these drawbacks are avoided.

The main feature of the invention consists in this that the weight of the tiltable portion 45 or portions of the grate is so distributed with respect to the axis of rotation that for the opening operation a small movement will suffice to cause the centre of gravity to shift from the one to the other side of the axis of rotation and automatically complete the opening.

Another feature of the invention consists in this that the axis of rotation of the tiltable portion of the grate is arranged to lie 55 below the centre of gravity of the same.

The invention also consists in limiting the

end position of the tiltable portion of the grate when open, by a rod, such a rod being preferably used also for limiting the end 60 position of the said grate when closed.

A still further feature of the invention consists in constructing the tiltable portion of the grate preferably in the form of an arc so that during the opening operation the same essentially performs a sliding movement with respect to the clinker above it.

The invention also consists in tapering those inside surfaces of the stationary grate which face the tiltable portion of the grate 70 in the direction of movement of the same, in such a manner as to allow the tiltable portion freely to be moved along a comparatively long arc.

Referring to Figs. 1 and 2 of the drawings which illustrate in sectional elevation and plan view respectively a grate with two 75 tiltable portions, 1 is a stationary part of the grate which stationary part is constructed in the form of ordinary flat fire bars resting on the usual supporting bars of the grate. 80 7 is the shaft of the tiltable portion 6 of the grate. The bearings for the tiltable portion are provided partly in the same and partly in the stationary portion of the grate. A cross pin or rod 8 is mounted in the stationary part 1 of the grate and is arranged to pass through an arc-shaped or other slot 85 9 provided in the grate bars of the tilting portion.

The tiltable portion kept in its position 90 of rest by the greater weight of one of its arms, the pin 8 serving as an abutment or stop. A push with the fire hook on one arm of the tiltable portion 6 suffices to start its tilting, and produce a short movement of 95 the same until the centre of gravity has been shifted from the right hand side to the left hand side of the tiltable portion 6 shown on the drawing, the tiltable portion then automatically continuing its movement into the open position in which it is fixed by the rod or pin 8 which now abuts against the right hand side of the slot 9. When the tiltable portion is in this position it is open on both sides relatively to the rotary shaft 7 to allow 100 the clinker to be removed. The tiltable portion remains in this open position until it is returned into its closed position by striking against the upper arm of the tiltable portion 105 after the removal of the clinker.

110 During the opening operation the tiltable portion of the grate essentially performs

- a sliding movement with respect to the clinker above it. This arrangement has the further advantage that when the weight of the clinker above it is rather great the resistance encountered by the shifting action exerted upon the tiltable portion of the grate is not so large as the said tiltable portion only performs a sliding movement with respect to the clinker. The two end positions of each of the two tiltable portions of the grate are determined by the pins 8 engaging in the slots 9 provided in the grate. It is however, to be understood that the tiltable portions of the grate may be stopped in their end positions by bolts or pins 10 provided on the stationary part of the grate 1.
- The inside surfaces of the stationary part of the grate which face the tiltable portions of the grate in the direction of the movement of the latter are tapered in such a manner as to allow the grate freely to be moved along a comparatively long arc.
- What I claim is:—
1. A furnace grate for fire boxes or flues of locomotive boilers comprising in combination with a stationary part a portion capable of being tilted, the centre of gravity of which is eccentric with respect to its axis of rotation and the weight of which is so distributed with respect to the axis of rotation
  2. A furnace grate as claimed in claim 1 and in which the axis of rotation of the tiltable portions of the grate lies below the centre of gravity of the latter.
  3. A furnace grate as claimed in claim 1, having a rod for limiting the end position of the tiltable portion of the grate when open.
  4. A furnace grate as claimed in claim 1, and having a rod for limiting the end position of the tiltable portion of the grate when opened and also its end position when closed.
  5. A furnace grate as claimed in claim 1, and in which the tiltable portion of the grate is constructed in the form of an arc and the inside surfaces of the stationary part of the grate which face the tiltable portions of the grate are tapered so that during the opening operation the said portion of the grate essentially performs a sliding movement with respect to the clinker above it.

that for the opening operation a small movement will suffice to cause the centre of gravity to shift from the one to the other side of the axis of rotation and automatically complete the opening.

2. A furnace grate as claimed in claim 1 and in which the axis of rotation of the tiltable portions of the grate lies below the centre of gravity of the latter.

3. A furnace grate as claimed in claim 1, having a rod for limiting the end position of the tiltable portion of the grate when open.

4. A furnace grate as claimed in claim 1, and having a rod for limiting the end position of the tiltable portion of the grate when opened and also its end position when closed.

5. A furnace grate as claimed in claim 1, and in which the tiltable portion of the grate is constructed in the form of an arc and the inside surfaces of the stationary part of the grate which face the tiltable portions of the grate are tapered so that during the opening operation the said portion of the grate essentially performs a sliding movement with respect to the clinker above it.

In testimony whereof I have signed my name to this specification.

KOLOMAN REZSNY.
